TOY PLAYGROUND

Irving L. Rabb, Norwalk, Conn., assignor to Grebar Toys
Inc., New York, N. Y., a corporation of New York

Application February 28, 1955, Serial No. 34,752

Term of patent 3½ years

(Cl. D34—15)

The figure is a perspective view of a toy playground showing my new design.

I claim:

The ornamental design for a toy playground, substantially as shown.
